GARMENT FASTENER

Daniel I. Reiter, New York, N. Y.

Application September 10, 1941, Serial No. 410,230

6 Claims. (Cl. 24—218)

This invention relates to garment fasteners and particularly to resilient sockets of the spring-wire socket type designed to withstand laundering of the garment to which the fastener is applied.

Socket fasteners of the resilient type designed to receive a cooperating stud have heretofore been attached to garments of comparatively thin and fragile material, such as dresses, by sewing the socket thereto with needle and thread. This mode of securing the socket to the garment is slow and hence uneconomical.

My invention therefore contemplates the provision of a resilient spring-wire socket provided with a one-piece housing having means for bending and holding the prongs of a pronged cap passed through the material of a garment into engagement with said means, and thereby securing the socket to the cap with the garment material therebetween by merely pressing the cap and socket together in an axial direction without the necessity for sewing.

My invention further contemplates the provision of a one-piece wire housing for a resilient spring-wire socket, said housing having an outwardly turned annular central part to guide the prongs of a pronged cap into a suitable socket-holding and securing position, and having a rim to hold the thus bent prongs in place, the entire housing being sufficiently thin to withstand laundering and pressing operations on the garment without damage.

The various objects of the invention will be clear from the description which follows and from the drawing, in which,

Fig. 1 is a vertical section of my improved socket fastener shown assembled with a cooperating stud and fastened to a garment.

Fig. 2 is a top plan view of the same, part of the garment being cut away to show the socket.

Fig. 3 is a similar view, partly broken away, of the socket housing and of the spring wire carried thereby.

In the practical embodiment of the invention shown by way of example, the socket housing 10 is secured to a part 11 of the garment by means of the pronged cap element 12. To another part 13 of the garment is secured the stud element 14 of any suitable and well known construction designed to be separably attached to the socket by the engagement thereof with the wire spring 15.

The housing 10 is of peculiar construction, being formed of a single piece of sheet metal bent to provide not only adequate means to hold the spring 15, but also to provide means to bend the prongs 16 of the cap element 12 as said cap is pressed toward the housing with the garment material therebetween. For holding the

wire spring, the base or plate-like part 17 of the housing is provided at its outer periphery with the upstanding circular rim 18 of arcuate cross-section and terminating in a circular free edge 19 overhanging the base 17 and spaced thereabove enough to make the resulting space 20 sufficiently large for the reception of the circular outer part 21 of the spring 15 in the lower part of the space and on the base and for the arrangement of the ends of the prongs 16 when bent in the upper part of said space above the spring and underneath the edge 19.

In the base 17 is provided a central opening 22 for the passage of the stud 14. Upstanding from the base is the substantially cylindrical wall 23 integral with the housing. Said wall surrounds the opening 22 and is arranged inside of the rim 18, being of greater height and extending above the rim as viewed in Fig. 1. The wall 23 is integrally joined by the bend 24 at its lower end to the base 17 and at its upper end is provided with the integral outwardly bent prong-bending wall 25 joined thereto by the integral annular bend 26. The wall 25 is preferably of generally conical shape, being of greater diameter at its lower free end than at its upper end where it joins the bend 26. Said wall 25 may also be curved concavely upwardly at its extremity 27 so that when the prongs 16 contact therewith and are pressed axially, said prongs are directed outwardly by the wall 25 and bent to a position underneath the peripheral part of the rim 18 as shown in Fig. 1. The thus bent prongs permanently secure the cap and socket together against separation from the garment and from each other without necessity for sewing or any other securing operation.

The wall 23 is cut away at two diametrically opposed parts thereof to form the spaced non-diametrical slots 28, 29 extending partway through said wall and having a height slightly greater than that of the diameter of the wire of the spring 15. From the circular part 21 of said spring are bent the parallel preferably straight legs 30, 31 which pass through the slots 28, 29 and through the interior space surrounded by the wall 23 and lie on or close to the base 17 of the housing. Said legs 30, 31 form the securing means to hold the stud 14 removably in the socket, being urged inwardly toward each other and against the inner edges of the slots in the wall 23 by the spring action of the circular part 21. The legs are free to yield or to move away from each other and partly out of said slots under the pressure of the stud head 14 forced therebetween after passage of said head through the opening 22.

It will thus be seen that the spring legs 30, 31 yield outwardly on the passage of the enlarged part of the stud head through the opening 22

and into the interior of the wall 23 and that said legs when released by the stud move toward each other to engage the constricted neck of the stud, thereby to hold the stud separably in position.

To secure the housing 10 to the garment part 11, the pronged cap 12 is provided. While the cap is shown in the form of a flat annular washer part with prongs at spaced intervals depending from the inner peripheral edge 33 of the washer part, it will be understood that the cap may be a closed cap of the type well known in the art and as is shown for example in my co-pending application Serial No. 388,962. No further description or illustration of the cap is therefore deemed necessary.

To assemble the cap 12 with the housing 10, said cap is arranged on one side of the material 11, while the housing is arranged on the other side of said material. The two parts are then moved toward each other to insert the prongs 16 through the space 34 between the housing part 25 and the extremity 19 of the rim, the prongs being forced into contact with the outer surface of the comparatively rigid wall 25 and being guided thereby and by the end part 27 thereof toward the rim and into the upper part of the space 26. The prongs are thereby bent into a position underneath the overhanging part of said rim and engage the rim and prevent the separation of the cap and housing from the garment.

While the wall 23 is open at its top as well as at its bottom owing to the formation of the outwardly extending wall 25, the garment part 11 covers and conceals said walls since some of the garment material is arranged inside of and bridges the space between the prongs on the inside of the cap 12. It will be seen that by the provision of the prong-bending wall and of sufficient space in the rim for the ends of the prongs, I have provided a simple one-piece prong-bending housing and fastener installation capable of quick and easy assembly to the garment without sewing and hence well designed for practical use.

I claim:

1. In a garment fastener, an annular base part having a central stud-receiving opening therein, an arcuate rim on the base terminating in a free edge, a wire spring having a circular part at the juncture of the base and rim and having a pair of spaced legs coplanar with and extending from the circular part across the base part, a wall of circular cross-section upstanding from the base part and surrounding the opening, said wall having spaced cut-away parts therein for the passage therethrough of the legs of the wire spring, and an annular prong-bending part extending downwardly and outwardly from the top of the wall and downwardly past and in inward spaced relation to the edge of the rim to form a prong-receiving space therebetween.

2. In a garment fastener, a dished one-piece housing having a central stud-receiving opening and a substantially cylindrical upstanding wall surrounding the opening, said wall being open at the upper end thereof, an outwardly and downwardly directed substantially conical wall extending integrally from the upper end of the cylindrical wall and terminating in a free edge, an upwardly and inwardly curved rim on the housing having a free circular edge arranged adjacent the conical wall and in outward spaced relation thereto to provide a prong-receiving space therebetween, and a spring ring having an intermediate part thereof arranged at the rim

and having the end parts thereof arranged in transverse spaced relation and passing through the cylindrical wall.

3. In a garment fastener, a one-piece housing having a central hollow cylindrical wall open at both ends thereof and having a pair of parallel slots therein, a base extending outwardly from one end of the wall and terminating in a peripheral rim of arcuate cross-section, the major part of said rim being sufficiently spaced from the base to provide a space therebetween of substantial height, a wire spring member having an arcuate part arranged in part of said space and having a pair of substantially parallel legs each arranged in one of said slots, the remainder of said space being sufficient for the reception of the bent prongs of a pronged cap, and a substantially conical prong-bending wall extending integrally and outwardly from the other end of the cylindrical wall and terminating in a free edge adjacent said space.

4. In a garment fastener, a resilient socket including a one-piece housing, said housing comprising a substantially flat base provided with an upstanding rim terminating in a free edge spaced from and overhanging the base, an integral upstanding wall on the base inside of the rim, and a prong-bending wall depending from the upstanding wall and arranged between the upstanding wall and said free edge of the rim, a wire spring having a circular part on the base at the rim, said free edge being arranged in vertical spaced relation to the spring to provide a prong-receiving space between the spring and said edge, and movable legs on the spring passing through the upstanding wall and movable away from each other under the pressure of a cooperating stud, and movable toward each other under the influence of said circular part of the spring.

5. In a garment fastener installation, a cap provided with bendable spaced prongs, a one-piece socket housing comprising a rim arcuate in cross-section, an annular wall in inward spaced relation to the rim and having a prong-bending wall depending therefrom and arranged between the rim and the annular wall, said annular wall having spaced slots therein, a wire spring arranged in part in the housing at the rim and having coplanar leg parts passing through the slots, the prongs of said cap passing through the space between the rim and the prong-bending wall and being bent by the prong-bending wall and directed thereby into the rim above the spring when the cap and housing are pressed together with a garment therebetween to secure the fastener to the garment.

6. In a garment fastener, a one-piece housing having a stud-receiving opening and a substantially cylindrical upstanding wall surrounding the opening, said wall being open at the upper end thereof and being provided with a pair of spaced transverse slots, an outwardly and downwardly directed substantially conical wall extending integrally from the upper end of the cylindrical wall, an upwardly and inwardly curved rim on the housing having a free circular edge arranged adjacent the conical wall and in outwardly spaced relation thereto to provide a prong-receiving space therebetween, and a spring ring having an arcuate part arranged below the free edge of the rim and having a pair of legs extending from the arcuate part and passing through the respective slots of the cylindrical wall.
